UNITED STATES PATENT OFFICE.

WELLINGTON P. KIDDER, OF ROCHESTER, NEW YORK, ASSIGNOR TO ROCHESTER INDUSTRIES, INC., OF ROCHESTER, NEW YORK, A CORPORATION OF NEW YORK.

TYPEWRITING MACHINE.

Application filed May 28, 1924. Serial No. 716,492.

My invention relates to improvements in that form of typewriting machines having end thrust type bars. One object of my invention is to combine toggle joint leverage 5 pressure with impact to reduce noise, as compared with the ordinary hammer blow of ordinary machines. Another object is to provide a more effective kick back for quickly returning the type to position of rest upon release of keys. A further object is to provide 10 a laterally central and more exact register of shift positions of carriage especially when imprint very quickly follows shift.

To these and other ends the invention relates in certain improvements and combinations of parts, all as will be hereinafter more fully described, the novel features being pointed out in the claims at the end of the specification.

In the specification, reference is made to the accompanying drawings, the designating numerals on which refer to corresponding parts throughout.

In the drawings:

Figure 1 represents an assembled side elevation of a machine embodying the invention partly in section through line A—A in Fig. 2 showing typebar action in normal position of rest, and the carriage in lower position for writing the lower case letters.

Figure 2 is a top plan view of the machine.

Figure 3 is a side elevation in section similar to that in Fig. 1 except with a type bar forward to impression position and carriage raised to capital shift position.

Figure 4 is a side elevation in section through line A—A of Figure 2 showing detail of carriage in upper or figure shift position.

Figure 5 is a rear elevation detail of parts of my central shift stops.

Figure 6 is a plan of Figure 5.

Figure 7 is an end elevation partly in section through line A—A of Figure 5.

Similar reference numerals throughout the several views indicate the same parts. Other parts of a writing machine are so well known that they are shown only in so far as needed to make the construction and operation of my novel features understood.

In my invention the type heads are radially mounted and rest by gravity on a horizontal flat plate guide, common to them all, the direction of motion of each, converging to a

common printing point, laterally guided at 55 the printing point by two pairs of side guides diverting angles of approach to a direct right angle pressure of each type face against the paper.

The actuating mechanism of each type bar 60 is laterally within and between the planes of the two sides of the type heads, thereby minimizing the lateral space occupied and consequently the length of type bar stroke required. By this arrangement the outside dimensions of the machine are brought within very small compass, and provided with extremely quick and easy key action. Embracing extreme simplicity, a further major advantage is in permanency of alignment. 70

Referring to the drawings, 3 represents the two main side frames, 4 the rear cross member, 5 the intermediate cross member and 6 the front cross member, each preferably L-shape as indicated, the latter cross member 75 adjacent to the key board. These frame parts are riveted or spot welded together, substantially integral.

On cross members 5 and 6, a radially slotted horizontal plate, 7, is attached by screws, 8. 80 The radial slots, 9, (Fig. 2), preferably 28 in number, are equi-distant apart, each one in converging alignment with a common center, 10, at the printing point surface of the platen roll 12, the latter mounted in a vertically shiftable carriage to be later described.

Suspended horizontally and parallel under the radial plate, 7, held separated by four distance collars, 13 and 14, and clamped by four screws, 15 and 16, is provided a second radial 90 plate, 17, with corresponding slots in vertical alignment and parallel with slots, 9, of plate 7. Screw heads, 15^A of the two screws, 15, are elongated downward to receive a horizontal curved pivot rod, 19, in the arc of a radius to the common center, 10.

Secured by four screws, 20, tapped in plate, 7, a hardened flat plate, 21, is laid on plate 7, on which the type heads, 22, of the type bars, 23, rest by gravity and slide to the printing point, 10, from position shown in Fig. 1 to that of Fig. 3, one pair of the side guides, 24 and 25 is secured to plate 21 by the same four screws, 20, through plate 21 and tapped in plate 7. A corresponding upper pair, 26, 105 of side guides, vertically over the lower ones at the printing point, is mounted on upright post 27, also fast to plate 21 by the screws,

20, being an integral extension of the guide 25.

To the front end of each of the type bars, 23, is pivotally connected at 28 a swinging bell crank lever, 29, laterally guided in a slot of the radial plate, 7, and also in a companion slot directly beneath it in plate, 17, the lower end of the bell crank lever, 29, pivotally mounted on the curved pivot rod, 19. Pivotally connected to one arm of the bell crank 29 at 30, is provided a link, 30^A, its lower end pivotally connected at 30^B to a key lever, 31, pivotally connected at its rear end on a pivot rod, 32, secured in two brackets 33 and 34, fast to rear cross member, 4, of the frame. The front end of the key lever is provided with an ordinary finger key, 31^A.

Preferably, 28 key levers and keys with 28 corresponding links, bell crank levers and type bars, with three type characters on the rear end of each type bar, printing 84 characters, with double vertical shift of carriage, are preferred.

On the bellcrank end of each bell crank actuating lever 29, is provided a ledge, 29^A, which upon approaching position shown in Fig. 3, contacts with a thin elastic curved metal wire rail, 36, the plan of which is shown in Fig. 2. The ends of this rail are secured at 36^A and 36^B, in a rocker shaft, 37, mounted on pivots, 37^A and 37^B, fast in the side frames, 3. On this rocker shaft is secured one end of a lever, 38, to the opposite free end of which is pivotally mounted one end of a pull spring 39, its opposite end anchored to a stud 40, fast in one of the side frames, 3.

In normal position of rest, with rail in its upper position shown in Fig. 1, the spring pull is nearly in alignment with center of rocker shaft, offering slight resistance or shock to contact of ledge, 29^A, but with progress of downward motion of rail, the direction of spring pull acts on an increasing and consequently lengthening of leverage of lever, 38, as shown in Fig. 3, thereby insuring a quick and powerful kick back or return of the ledge-formed lever, with its pivoted type bar, to normal, upon release of its key, forming one important feature of my invention.

Fast to rocker shaft 37 at 38^A is placed a duplicate of lever 38 pivotally connected with rearwardly extending link 38^B for actuating any convenient form of escapement mechanism for the carriage and for a ribbon feed, too common in other writing machines to need further reference.

I preferably support the paper carriage on an ordinary ball bearing race way, the forward member, 41, of which, having both a vertical and longitudinal movement carrying the platen, 12, feed roll, 43, and other ordinary parts of a paper carriage, too well known for further reference.

The rear supporting member, 45, is provided with movement in a vertical plane only,

pivotedly supported on two pivots, 46 and 46^A, at the rear ends of a pair of shift key levers, 47, and 47^A, fast on a rocker shaft, 48, pivoted at either end on studs 48^A and 48^B, screwed in the side frames, 3, the forward end of the lever 47 fixed to shift key, 47^A. The vertical action of the rear member 45 being further controlled by a pair of bent arms, 49 and 50, riveted to 45 and guided on a pair of vertical posts, 51 and 52 fast in lower cross member, 75 4, of the frame. The lower bent ends of arms, 49 and 50 provide the bearings for the pivots, 46 and 46^A.

It now remains to describe and illustrate my centrally located shift stops for paper carriage.

At the center length of the rear cross member, 4, of the frame, is provided an upward widening, 4^A, more clearly shown in rear elevation in Fig. 5, and in end elevation in Fig. 7, the latter in section through line A—A of Fig. 5, and in plan, Fig. 6. Adjustably attached by clamping screws, 53, and adjusting screw, 54, is provided a bent plate, 55, its upper bent end, 55^A, in the path of a U-shaped bent plate, 56, (Fig. 1; 3 and 4), riveted fast to the rear member, 45, of the carriage. The upper bent end, of plate, 56, is provided with an adjusting screw, 57^B, with locking nut, the lower end of which 95 screw contacts with upper surface 55^A of bent plate 55, forming an adjustable stop for the carriage in its lowest, or lower case stop position, as shown in Figure 1. In the upper stop, or figure shift position, the under side of the bent end, 55^A of plate, 55 contacts with the upper side of lower bent end of plate 56, made adjustable by screws, 54, tapped in base member 4, secured by lock nut, 55^B, (Figs. 1 and 2).

Midway between the above lower and upper stop limits of the carriage, I provide a movable stop, 57 in the path of the lower bent end of plate 56. This movable stop contacts at its upper edge with under side of bent end 55^A of plate 55 and forms the register stop of carriage in its midway or capital shift position, at which time it contacts at its lower edge with the upper side of lower bent end of plate 56. A slot 55^E (Fig. 5) is provided 115 in bent plate 55, through which this movable stop plays with clearance. It is moved out of the way, in shifting to upper or figure shift position, by means of a figure shift key, 58, on front end of an offset bell crank lever, 59, pivoted on stud, 60, fast in a bracket 60^A fast to frame member 6. The lower arm of the bell crank lever, 59, pivotally connected at 61 with long bent connecting rod, 62, its rear end pivotally connected to lever 57^A at 125 57^B, one end of which lever is pivotally connected at 57^C on a stud fast in cross member, 4, of the frame, the other end integral with the movable stop, 57. Upon depressing key 59 the stop, 57, is moved to the rear, out of 130

the way, the continued depression of key 59 contacting with arm, 47, carrying the shift key 47^A down to figure shift position.

The movable stop, 57, is not removed from the path of 56 when registering the capital shift position (see Fig. 3). For capital shift, merely the shift key, 47^A is depressed. Pull spring 47^B and a similar one for bell crank lever 29 return parts to normal on release of 10 keys.

The utility and advantages of my several novel features will be clear from the foregoing description of the construction and operation. By the combination of toggle joint leverage pressure nearly one half of the printing pressure required is noiseless, materially reducing the supplemental violence of the impact, without which combination with impact much more complicated and expensive mechanism is necessary to make successful a pure toggle device both as to sufficient pressure and sufficient speed with sufficiently easy action.

Not only does my combination greatly simplify the working parts for low cost production but makes possible the construction of a much smaller and lighter machine for portable use.

The value of my centrally located stops 30 for registering the vertical shift positions of the carriage, the stops in lateral alignment with the printing point, is evident when it is considered that no elasticity or lost motion at either end of the carriage in 35 any position of its travel can impair the absolute register of capitals with lower case or figures at the printing point.

With respect to the kick back rail in combination with the ledges of the bell crank 40 levers pivotally connected to one end of type bars, it is seen that practically nothing is added to initial resistance in starting the depressions of a key, while the progressive resistance of the rail insures a very quick 45 turn when key is released.

I claim as my invention:

1. A typewriting machine comprising an end thrust type bar, a horizontally disposed plate supporting and guiding said bar and 50 having a slot therein, a pivotally supported bell crank lever having an end projecting upwardly through said slot and pivotally connected with said bar, operating means for swinging said bell crank lever in one direction to effect an impression by said bar, a shoulder on said lever, a pivoted rail lying in the path of movement of said shoulder and normally spaced therefrom whereby no 55 resistance is offered to the initial depression of the keys, and spring means supporting said rail to restore the latter to position after impact by said shoulder to return said lever in the other direction.

2. A typewriting machine comprising an 60 end thrust type bar, plate means supporting

and guiding said bar, a pivotally supported bell crank lever having an end pivotally connected with said bar, vertically spaced plates provided with aligned slots receiving and guiding said lever, operating means for 70 effecting an impression movement of said lever, and means including a pivotal support and a yieldable element thereon in the path of and normally spaced from the lever for partially retarding the impression movement 75 of said lever and for effecting return movement thereof, said means being normally spaced from and in the path of the lever whereby the initial movement of the latter toward the printing point is unretarded by 80 said means.

3. In a typewriting machine, a frame, a horizontally disposed plate carried thereby having a series of radial slots therein, a series of bell crank levers projecting through said 85 slots having their upper ends overlying the plate and their lower ends pivoted therebeneath, end thrust type bars pivotally connected with the upper ends of the levers and adapted to have a swinging and sliding 90 movement upon said plate, a key lever operatively connected with each of the bell crank levers, a carriage having a platen located in advance of the limit of movement of said 95 bars to afford impression of the type by combined impact and toggle pressure, a transverse bar pivoted upon the frame, a spring normally holding said bar in a predetermined position and a rod secured to and projecting from said bar and normally spaced 100 from and in the path of the bell crank levers to be engaged by the latter subsequent to initial operation thereof.

4. A typewriting machine comprising an end thrust type bar, toggle mechanism for 105 actuating said bar, a platen located in advance of the limit of movement of said bar by said mechanism to afford a combination of toggle pressure with impact speed and ease of operation, an operating member, a connection between said operating member and toggle mechanism adapted to operate the latter and a yieldable member normally spaced from said toggle mechanism and adapted to be engaged by the latter when moving to advance the type bar toward the 110 platen adapted to partially retard the impression movement of the toggle and for effecting return movement thereof.

5. In a typewriting machine, the combination of an end thrust type bar, toggle mechanism comprising a bell crank lever connected with said bar, a platen located in advance of the limit of movement of said bar by said mechanism to afford a combination of toggle 120 pressure with impact speed and ease of operation, a key lever, a link pivotally connected with said key lever and with said bell crank lever to swing the latter to effect impression movement of said bar and a yieldable mem- 125 130

ber normally spaced from said bell crank lever and adapted to be engaged by the latter when moving to advance the type bar toward the platen for partially retarding the impression movement of said lever and for effecting return movement thereof.

6. In a typewriting machine, the combination of an end thrust type bar, plate means supporting and guiding the type end of said bar, toggle mechanism pivotally connected with the other end of said bar, spaced guides, a support vertically shiftable upon said guides, a carriage on the support having a platen located in advance of the limit of movement of said type bar by said mechanism to afford a combination of toggle pressure with impact speed and ease of operation, stop means for limiting the shifting movement of said support located opposite the impression point and between said guides, a key lever and a link pivotally connected with said lever and with said toggle mechanism to actuate the type bar.

7. A typewriting machine, comprising a frame, spaced guides upon the frame, a support vertically shiftable upon the guides, a platen carriage vertically shiftable with the support on said guides for case selection, means for shifting said support and positive stops located on said frame between said guides and opposite the impression point for insuring accurate shift register of said carriage.

8. A typewriting machine, comprising a frame, a support shiftable vertically upon the frame and having a platen carriage thereon, a pair of connected levers pivoted upon the frame and extending transversely of the carriage and having their rear ends directly connected with the support to effect raising of the same, one of the levers being extended to the front of the machine to provide an operating member for raising the support, fixed and movable stops for the support, manually operable means for shifting the movable stop to clear the support, an end thrust type bar having vertically spaced printing characters thereon, toggle mechanism for actuating said bar and a key lever operatively connected with the toggle mechanism. 50

9. In a typewriting machine, a frame, a platen carriage having a platen thereon, a support for said carriage adjustable vertically to different positions upon the frame, a type bar having spaced printing characters 55 for cooperation with the platen in different positions of adjustment thereof, operating means for said type bar, fixed and adjustable stops for said support, a lever for raising the support when the adjustable stop is in operating position and means including a second lever adapted upon initial operation to shift the adjustable stop and to subsequently operate the first mentioned lever whereby to raise said support. 60

WELLINGTON P. KIDDER.
